UNITED STATES PATENT OFFICE.

WALTER G. TURPISCH, OF STAPLETON, NEW YORK.

DESIGN FOR A DISPLAY STAND.

Application filed August 28, 1925. Serial No. 14,626. Term of patent 7 years.

To all whom it may concern:

Be it known that I, WALTER G. TURPISCH, a citizen of the United States, residing at Stapleton, in the county of Richmond and State of New York, have invented a new, original, and ornamental Design for Display Stands, of which the following is a specification, reference being had to the accompanying drawing, forming part thereof and in which—

Figure 1 is a top plan view of a display stand, showing my new design,

Figure 2 is a front elevational view of the same, and

Figure 3 is a transverse sectional view of the same.

I claim:—

The ornamental design for a display stand as shown.

WALTER G. TURPISCH.
